Specification of Letters Patent.

Patented Sept. 2, 1913.

Application filed June 20, 1912. Serial No. 704,933.

To all whom it may concern:

Be it known that we, BENJAMIN F. CLINE and JESSE F. HENSLEY, citizens of the United States, and residents of Indianapolis, county of Marion, and State of Indiana, have invented a certain useful Sign; and we do hereby declare that the following is a full, clear, and exact description thereof, reference being had to the accompanying 10 drawings.

The object of this invention is to provide a sectional or built up sign of improved and simplified construction.

The feature of the invention lies in the 15 use of sectional front or letter carrying plates, intermediate perforated sheets and rear or clamping plates, all of standardized construction such that the building of any desired sign will be quickened and simplified.

The nature of the invention will be understood from the accompanying drawings and the following description and claims.

In the drawings, Figure 1 is a front elevation of the same. Fig. 2 is a rear elevation of the same. Fig. 3 is a transverse section on the line 3—3 of Fig. 2. Fig. 4 is a plan view of the rear side of the clamping plate. Fig. 5 shows the perforated frame 20 member shown in Fig. 3 but removed from the sign. Fig. 6 is a perspective of one section of the sign with portions broken away showing the relation of the various parts.

In detail there is shown in the drawings 35 a built up sign having front plates 10, rear or clamping plates 11 with a plate of perforated material 12 secured between the two and with the various sections thus built up, assembled and supported by longitudinal 40 rods 13 at the rear side of the front plate 12.

As shown in details in Figs. 1, 3 and 6, the front plate 10 is formed of thin sheet metal with a portion therein cut away in the form of a letter or character and having 45 a rib 14 upon one side, here shown upon the left-hand side, which projects behind the adjoining plate 10 and serves to strengthen the sign in addition to closing the joint between the adjacent plates 10. There 50 is a projection 15 from the rear side of the front plate and near the upper and lower edges and substantially midway between the sides in which there is a hole 16 for the rods 13 upon which said front plates 10 are supported. There is a notch 17 cut in the projection 15 close to the plate 10 upon the in-

ner side or adjacent the letter or character opening into which the ends of the clamping plate 11 are slipped or slid into place for the purpose of holding the intermediate 60 plate 12.

The clamping plates 11 are substantially rectangular in outline and have the ends 18 flattened to permit them to be inserted in the notches 17 in the projections 15 of the 65 front plate 10. The side bars 19 of said frame are preferably very narrow and the distance between them is equal to the width of the character cut on the front plate. Said side bars may have a depth materially 70 greater than their thickness, as shown in Fig. 3.

The intermediate plate 12 may be formed of perforated sheet metal, as shown in Figs. 1, 2 and 6. Said plate has the same general 75 outline as that of the clamping plate 11, but has its edges upon two sides bent at right angles to fit snugly over the narrow side ribs of the clamping plate 11.

Our invention is assembled as follows: 80 The perforated intermediate plates 12 are first slid upon the front face of the clamping plate 11, after which said clamping plate is slid into place upon the rear side of the front plate 10 which has the desired 85 opening cut through it and held by means of the notches 17 in the rearward projections 15 and with one edge of the intermediate plate pressed against the rib 14 by one of the side bars of the clamping plate 11. 90 This forms one unit of the sign. Other units with the desired openings are assembled in a like manner and they are combined in the desired order and the rods 13 are 95 slipped through the holes 16 in said projections, with the ribs 14 of one plate lying immediately behind the edge of the adjacent plate. The sign may then be hung or used in any desired manner.

We claim as our invention:

1. A sign composed of a plurality of similar sections, each section having a front plate with an opening therethrough, a clamping plate with a portion thereof cut away and in registry with said front plate 105 opening, a perforated sheet between said front plate and said clamping plate, means for slidably securing said clamping plate to said front plate for clamping said perforated sheet, and means connecting with 110 said supporting means for securing said sections in place in series.

2. A sign composed of a plurality of similar sections, each section having a front plate with an opening therethrough, a skeleton clamping plate adjacent thereto with an opening therethrough in registry with the opening in said front plate, the ends of said clamping plate being flattened, a perforated sheet between said front plate and said clamping plate and with the edges of said sheet bent against the lateral edges of said clamping plate, notched projections on said front plate for slidably engaging the flattened ends of said clamping plate, and means for supporting said sections in series.
- 5 3. A sign composed of a plurality of similar sections, each section having a front plate with an opening therethrough, one lateral edge of said front plate being recessed and adapted to extend behind the next one of said front plates, a skeleton
- 10 clamping plate of substantially the same outline as said front plate, an open-work sheet located between said front plate and said clamping plate and having the lateral edges thereof bent against the sides of said 25 clamping plate, recessed projections on said front plate slidably engaging the ends of said clamping plate and clamping said open-work sheet against said front plate, and a rod extending through one of said 30 projections on each front plate for assembling said sections in series.
- 15 In witness whereof, we have hereunto affixed our signatures in the presence of the witnesses herein named.
- 20 BENJAMIN F. CLINE.
JESSE F. HENSLEY.
